(57) **CLAIM**

The ornamental design for a puzzle game, as shown and described.

DESCRIPTION

The patent or application file contains at least one drawing executed in color. Copies of this patent or patent application publication with color drawing(s) will be provided by the Office upon request and payment of the necessary fee.

1. Puzzle game

1.1 is a right side view of a puzzle game;

1.2 is a top view thereof;

1.3 is a bottom view thereof;

1.4 is a front view thereof;

1.5 is a left side view thereof;

1.6 is a back view thereof;

1.7 is a first perspective view thereof;

1.8 is a second perspective view thereof;

1.9 is a third perspective view thereof;

(Continued)

1.10 is a fourth perspective view thereof;
1.11 is a fifth perspective view thereof; and
1.12 is a sixth perspective view thereof.
